(57) **CLAIM**

The ornamental design for a propulsion unit for a toy plane, as shown and described.

DESCRIPTION

FIG. 1 is a front view of a first embodiment of a propulsion unit for the toy plane.

FIG. 2 is a rear view of the propulsion unit for the toy plane of the first embodiment.

FIG. 3 is a left view of the propulsion unit for the toy plane of the first embodiment.

FIG. 4 is a right view of the propulsion unit for the toy plane of the first embodiment.

FIG. 5 is a top view of a first embodiment of a propulsion unit for the toy plane.

FIG. 6 is a bottom view of the propulsion unit for the toy plane of the first embodiment.

FIG. 7 is a front left 45-degree view of the propulsion unit for the toy plane of the first embodiment.

FIG. 8 is a front right 45-degree view of the propulsion unit for the toy plane of the first embodiment.

FIG. 9 is a rear left 45-degree view of a first embodiment of a propulsion unit for the toy plane.

FIG. 10 is a rear left 45-degree view of the propulsion unit for the toy plane of the first embodiment.

FIG. 11 is a front view of a third second embodiment of a propulsion unit for the toy plane.

FIG. 12 is a rear view of the propulsion unit for the toy plane of the second embodiment.

FIG. 13 is a left view of the propulsion unit for the toy plane of the second embodiment.

FIG. 14 is a right view of the propulsion unit for the toy plane of the second embodiment.

FIG. 15 is a top view of the second embodiment of a propulsion unit for the toy plane.

FIG. 16 is a bottom view of the propulsion unit for the toy plane of the second embodiment.

FIG. 17 is a front left 45-degree view of the propulsion unit for the toy plane of the third embodiment.

FIG. 18 is a front right 45-degree view of the propulsion unit for the toy plane of the second embodiment.

FIG. 19 is a rear left 45-degree view of the second embodiment of a propulsion unit for the toy plane.

FIG. 20 is a rear right 45-degree view of the propulsion unit for the toy plane of the second embodiment.

FIG. 21 is a front 3-D view of a third embodiment of a propulsion unit for the toy plane.

FIG. 22 is a rear 3-D view of the propulsion unit for the toy plane of the third embodiment.

(Continued)

FIG. 23 is a left 3-D view of the propulsion unit for the toy plane of the third embodiment.

FIG. 24 is a right 3-D view of the propulsion unit for the toy plane of the third embodiment.

FIG. 25 is a top 3-D view of a third embodiment of a propulsion unit for the toy plane.

FIG. 26 is a bottom 3-D view of the propulsion unit for the toy plane of the third embodiment.

FIG. 27 is a front left 45 degree 3-D view of the propulsion unit for the toy plane of the third embodiment.

FIG. 28 is a front right 45 degree 3-D view of the propulsion unit for the toy plane of the third embodiment.

FIG. 29 is a rear left 45 degree 3-D view of a third embodiment of a propulsion unit for the toy plane.

FIG. 30 is a rear right 45 degree 3-D view of the propulsion unit for the toy plane of the third embodiment.

FIG. 31 is a front 3-D view of a fourth embodiment of a propulsion unit for the toy plane.

FIG. 32 is a rear 3-D view of the propulsion unit for the toy plane of the fourth embodiment.

FIG. 33 is a front left 45 degree 3-D view of the propulsion unit for the toy plane of the fourth embodiment.

FIG. 34 is a rear left 45 degree 3-D view of the propulsion unit for the toy plane of the fourth embodiment.

FIG. 35 is a front right 45 degree 3-D view of the fourth embodiment of a propulsion unit for the toy plane; and,

FIG. 36 is a top 3-D view of the propulsion unit for the toy plane of the fourth embodiment.
